UNITED STATES PATENT OFFICE.

ULRICH A. TADDIKEN, OF PHILADELPHIA, PENNSYLVANIA, ASSIGNOR TO WESTINGHOUSE ELECTRIC & MANUFACTURING COMPANY, A CORPORATION OF PENNSYLVANIA.

CONDENSING APPARATUS.

Application filed July 8, 1927. Serial No. 204,345.

My invention relates to heat exchangers and like apparatus, in which condensation, or in which ebullition and condensation take place, and it has for an object to improve the efficiency of apparatus of this character.

The air and other non-condensable gases, or vapors, which are present in the gaseous media passed into heat exchangers, such as surface condensers and the like, not only 10 preclude the possibility of obtaining a perfect vacuum, but also tend to retard circulation and to prevent complete condensation of the condensable gases.

Condensation leaves the non-condensable 15 gases on the condensing surface, from whence they must be removed by proper circulation. The quantity of non-condensable gases to be so removed, of course, increases with the progress of gaseous media 20 through a nest of cooling tubes, so that, in the later stages of the process, the non-condensable gases, which are also relatively poor conductors of heat, comprise a substantial proportion of the gaseous media present. 25 Hence, toward the completion of the process of condensation, the non-condensables, due to their low conductivity, tend to form an insulating medium and to delay the condensation of the condensable vapors approaching the condensing surface, and thus, 30 also to retard circulation.

Furthermore, the non-condensable gases exert a pressure which directly affects the 35 vacuum obtainable. According to Dalton's law of partial pressures, the pressure within a condenser, for example, is the total pressure of the gaseous mixture, or the summation of the partial pressures due to each of the respective gaseous constituents.

40 For example, assume the temperature at any point within a condenser to be 101° F., and that for each pound of steam there is present $\frac{1}{4}$ of a pound of air, a condition which is not uncommon. At 101° F. a pound 45 of steam occupies 341 cubic feet. This same space then, also contains $\frac{1}{4}$ of a pound of air. The pressure of steam at 101° F. is approximately 2" of mercury, which corresponds to a vacuum of 29.92-2 or 27.92 50 inches.

However, the partial pressure due to the air is .31 inches of mercury. From Dalton's law then, the total pressure is 2+.31 or 2.31 inches of mercury, which corresponds to a 55 vacuum of only 29.92-2.31 or 27.61 inches.

With one pound of air per pound of steam, which is a possible condition, the pressure due to the air would be 1.24 inches of mercury, under the same circumstances, and the vacuum would only be 26.68 inches. It 60 will readily be seen, therefore, that the partial pressure of the air has a very appreciable effect upon the vacuum, and that every precaution should be taken to prevent the air and other non-condensable gases from 65 accumulating, or concentrating in any portion of a condenser.

If some of the gaseous media which contains a relatively high proportion of the non-condensable gases is removed from an ex- 70 changer of the type described, the surface of this portion of the exchanger becomes more effective, due to the fact that gaseous media containing a lower proportion of non-condensable gases may reach this surface. 75

Furthermore, if the gaseous media, so removed, is introduced into the exchanger at some point where the proportion of non-condensable gases is somewhat lower, the proportion of non-condensable gases present in 80 the gaseous media throughout the exchanger becomes more uniform, the effect of the relatively low conductivity of these gases and of their partial pressures becomes less, and their concentration in certain regions is 85 avoided.

More particularly, therefore, an object of my invention is to provide means for removing gaseous media from a portion of a condenser in which the proportion of non-condensable gases is relatively high and for passing the media so removed into the condenser in some region where the non-condensable gases are less concentrated, so that the mixture containing the relatively high 90 proportion of non-condensables may be assimilated by a larger volume of gaseous media having a somewhat lower content of non-condensables.

Apparatus embodying features of my in- 100 vention is shown in the accompanying drawings, in which;

Figs. 1 and 2 are transverse sections of downflow condensers;

Figs. 3 and 4 are transverse sections of 105 radial-flow condensers; and,

Fig. 5 is a detail view of a connection for removing gaseous media from the condenser shown in Fig. 4.

According to my invention, any suitable 110

fluid translating means is arranged to withdraw gaseous media from the vicinity of that region in a condenser wherein the process of condensation is completed. Preferably, I use a steam-operated ejector and provide an auxiliary heat exchanger for recovering the heat of the motive fluid, which actuates the ejector. The gaseous media withdrawn from the condenser has practically the same temperature as the condensate which serves as the cooling media for the auxiliary heat exchanger, and hence it is assured that the withdrawn gaseous media will pass through this auxiliary heat exchanger and be recirculated through the nest of condensing tubes.

Referring now to the drawings for a better understanding of my invention, I show, in Fig. 1, a straight down-flow condenser 10, comprising a shell 11, having a motive fluid inlet 12, and provided with a hotwell 13. The nest of cooling tubes 14 is separated, by the longitudinally-extending baffle 16, to provide a cooling chamber 17 for cooling the air and other non-condensable gases previous to their removal through the air removal connection 18.

The operation of the apparatus thus far described is well understood, motive fluid exhaust being passed into the shell through the inlet 12, passes through the nest of cooling tubes 14 where the motive fluid exhaust is condensed. As the gaseous media progresses through the nest 14, the continuous removal of the condensable vapors by condensation leaves a progressively increasing proportion of air and other non-condensable gases in the nest of cooling tubes, with the result that, in the lower portions of the tube nest 14, there is a tendency for the non-condensables to collect, or to become somewhat concentrated.

In order to prevent this condition, I provide suitable fluid translating apparatus here shown in the form of steam-operated ejectors 21, which are disposed along the bottom of the condenser shell on either side of the hotwell. One or more of these ejectors may be used, depending upon conditions, but, preferably, one such ejector and its associated connection are disposed on each side of the hotwell 13. Since the function of each of these ejectors is the same, only one will be described.

The ejector 21 is of the usual form and comprises an entraining chamber 22, a steam jet 23 and a diffuser 24. The entraining chamber 22 is connected with the lower portion of the tube nest 14 by the connection 26, this connection 26 being protected from the rain of condensate by a cowl, or the like, 27, so that during the operation of the ejector, gaseous media may be drawn under the cowl 27 and through the connection 26 to the entraining chamber 22 of the ejector,

from whence it is removed through the diffuser 24.

In order to recover the heat of the motive fluid which passes through the jet 23 to actuate the ejector 21, I connect the diffuser 24 to the steam space of a suitable heat exchanger 29, which is of the surface type, and is provided with a longitudinally-extending baffle 31 for preventing gaseous media from by-passing from the diffuser 24, through a portion of the nest, and to the connection 32 which is provided for the removal of gaseous media.

The condensate removal pump 33, for the main condenser is arranged to discharge into the connection 34, which connects with the circulating system of heat exchanger 29, the condensate being discharged from the heat exchanger 29 through the connection 36. In this way, it is possible to recover the heat of the motive fluid which issues from the jet 23 of the ejector 21 and entrains the gaseous media in the entraining chamber 22. The entrained media, having practically the same temperature as the condensate, which is used as cooling media in the exchanger 29, will, of course, not be condensed in the heat exchanger 29, but will pass around the baffle 31 and out from the heat exchanger 29 through the connection 32, from which it passes into the tube nest 14 at some suitable point, as at the connection 37. A baffle 38 is arranged to depend from above the connection 37 so as to protect the tubes of the nest 14, which are adjacent to the connection 37, from any vibration which might be caused by the passage of gaseous media through this connection.

The condensate, after passing from the connection 36 of the heat exchanger 29, may be utilized in any suitable manner, as for boiler feed water.

The condenser shown in Fig. 2, and also the apparatus shown for removing gaseous media from the tube nest 14, are in all respects similar to the arrangement shown in Fig. 1, with the exception that the heat exchanger 29 is omitted. In this case the entraining fluid which issues from the jet 23 of the ejector 21, as well as the gaseous media which is entrained, is passed directly from the diffuser 24 through the connection 32 into the nest of tubes 14, the entraining fluid as well as any condensable vapors in the entrained fluid being condensed in the nest 14.

In this case, the heat of the motive fluid which actuates the ejector 21 is not recovered, but the general improvement in the operation of the condenser is brought about as before. The cost of this apparatus is less than that shown in Fig. 1, due to the elimination of the heat exchanger 29.

In the arrangement shown in Fig. 3, a ra-

dial-flow condenser 40, comprising a shell 41, having a motive fluid exhaust inlet (not shown) is provided with a hotwell 43. A portion of the tubes of the nest 44 are separated from the condensing portion of the nest by spaced plates 46 and 47, to provide a cooling chamber 48 for cooling the air and the other non-condensable gases, previous to their removal through the air removal connection 49. The inner side, or portion, of this chamber is closed by a rain plate, or the like, 51, which rests on the upper ends of the plates 47, while the lower portion of the plates 46 are secured to the shell, the space between the plates 46 and 47 providing a passage for gaseous media from the condensing portion of the tube nest 44 to the cooling chamber 48. Condensate from the shell 41 passes through the connections 52 and 52' to the hotwell 43. A condenser of this type is fully described in the patent to Hodgkinson, No. 1,578,032, and is, therefore, only briefly referred to here.

In the form of my invention shown in Fig. 3, the connection 26 and its protecting cowl 27, are disposed in the lower portion of the cooling chamber 48 so that a portion of the gaseous media which enters the cooling chamber may be removed by the ejector 21 and returned to the tube nest 44 through connection 53, which, in this case, is for convenience arranged to pass the media into the tube nest 44 along a lower portion thereof. It will be observed that inasmuch as this is a radial-flow condenser, the path of vapor travel is substantially the same for gaseous media at any point about the periphery of the nest of cooling tubes.

In Fig. 4, a radial-flow condenser 54, comprising a shell 55, having a motive fluid exhaust inlet 56, is provided with a hotwell 57. The air and non-condensable gases are removed from the nest of cooling tubes 58 through the removal connection 59, which is protected from the rain of condensate by a rain plate 61.

In this form of apparatus, the connection 26 of the ejector 21 is connected to relatively short, longitudinally-extending pipes 62, by means of the connections 63 and 64. These pipes 62 appear in longitudinal elevation in Fig. 5, from which it will be observed that the open ends of the pipes are undercut, or biased, so as to permit gaseous media to enter either end of these pipes and to pass therefrom, through the respective connections 63 and 64, to the connection 26, while the projecting upper ends of the pipes serve to prevent condensed media from passing into these connections. The media withdrawn by the ejector, as well as the entraining fluid, is then passed from the ejector through the connection 66 and into the nest 58 for recirculation.

In Fig. 4, as well as in the other views, it

will be observed that gaseous media is removed only after it has passed through a considerable portion of the nest of cooling tubes, and thus it is assured that the media so removed will contain as large a content 70 of non-condensables as will be found in gaseous media in any portion of the condenser, and that this media is re-introduced into the nest of condensing tubes at the point where the proportion of non-condensable gases will 75 be relatively low. In this way it is possible to provide for maintaining a more uniform condition throughout the nest of cooling tubes, this being accomplished by mixing gaseous media having a high content of non- 80 condensables with gaseous media having a relatively low content of non-condensables.

It will thus be seen that I have provided means for preventing the non-condensable gases from concentrating in any portion of 85 a heat exchanger, and for assuring improved conditions for vapor flow and for maintaining the desired vacuum. It will also be obvious that my invention may be embodied in existing forms of condensing apparatus 90 without any material alterations in such apparatus.

Furthermore, the air removal apparatus is left to function as before, so that it is assured that the proper conditions of flow will 95 be obtained in the vicinity of the air removal connection, which, of course, would not be the case if the flow of gaseous media were merely accelerated by this apparatus in an endeavor to prevent the concentration of 100 the non-condensable gases.

While I have shown the heat exchanger 29 only in connection with a down-flow condenser, it will be understood that it is within the province of my invention to provide similar heat exchangers for radial flow condensers.

While I have shown my invention in several forms, it will be obvious to those skilled in the art that it is not so limited, but is 110 susceptible of various other changes and modifications without departing from the spirit thereof, and I desire, therefore, that only such limitations shall be placed thereupon as are imposed by the prior art or as 115 are specifically set forth in the appended claims.

What I claim is:—

1. The combination with a nest of tubes, of means for directing gaseous media through 120 the nest, and means for re-circulating some of the media through the nest.

2. The combination with a nest of tubes, of means for directing gaseous media through the nest, fluid translating means 125 for withdrawing uncondensed media from the nest, and means for passing media discharged by said fluid translating means into the nest.

3. A device of the type described compris- 130

ing a shell having an inlet for condensable gases, a nest of tubes within the shell, fluid translating means connected to the shell at a point remote from said inlet, and means 5 providing a passage from the discharge of the fluid translating means to the nest of tubes.

4. The combination with a surface condenser comprising a shell having a motive fluid inlet, a nest of tubes within the shell, and an offtake for air and non-condensable gases, of fluid translating means having an inlet in a path of vapor travel to said offtake, and means for passing media discharged by 10 said fluid translating means to the nest of tubes.

5. The combination with a surface condenser comprising a shell having a motive fluid inlet, a nest of tubes within the shell, 20 and an offtake for air and non-condensable gases, of fluid translating means having an inlet in a path of vapor travel to said offtake, a passage for passing media discharged by 25 said fluid translating means to the nest of tubes, and cooling means interposed in said passage.

6. The combination with a surface condenser comprising a shell having a motive fluid inlet, a nest of tubes within the shell, 30 a hotwell for the shell, and an offtake for air and non-condensable gases, of fluid translating means having an inlet in a path of vapor travel to said offtake, a passage for conducting media discharged by 35 said fluid translating means to the nest of tubes, cooling means interposed in said passage, and means for supplying cooling media for said cooling means from the hotwell.

7. The combination with a tubular heat 40 exchanger having a condensing portion and a cooling portion arranged for passing gaseous media therethrough in series, of means

for withdrawing gaseous media in the education side of the condensing portion from the exchanger, and means for recirculating 45 the withdrawn media through the condensing portion.

8. The combination with a tubular heat exchanger having a condensing portion and a cooling portion arranged for passing gaseous media therethrough in series, of fluid entraining means for withdrawing gaseous media from the education side of the condensing portion, means for recovering heat from the entraining fluid, and means for recirculating 50 the withdrawn media through the condensing portion.

9. The combination with a tubular heat exchanger having a condensing portion and a cooling portion arranged for passing gaseous media therethrough in series, of fluid entraining means for withdrawing gaseous media from the education side of the condensing portion, means for transferring heat from the entraining fluid to condensate from the 60 condensing portion, and means for recirculating the withdrawn media through the condensing portion.

10. The combination with a tubular heat exchanger having a condensing portion and a cooling portion arranged for passing gaseous media therethrough in series, of an offtake for removing air and non-condensable gases from the cooling portion, and means for withdrawing gaseous media from the region substantially between said condensing and said cooling portions and for diverting the media so withdrawn away from both the condensing portion and the cooling portion. 75

In testimony whereof, I have hereunto subscribed my name this 23rd day of June, 1927. 80

ULRICH A. TADDIEN.
